UNITED STATES PATENT OFFICE.

WILLIAM A. LORENZ, OF HARTFORD, CONNECTICUT.

HERMETIC CLOSURE FOR TUMBLERS.

No. 829,980.

Specification of Letters Patent.

Patented Sept. 4, 1906.

Application filed December 18, 1905. Serial No. 292,220.

To all whom it may concern:

Be it known that I, WILLIAM A. LORENZ, a citizen of the United States, and a resident of Hartford, in the county of Hartford and State of Connecticut, have invented certain new and useful Improvements in Hermetic Closures for Tumblers, of which the following is a full, clear, and exact specification.

This invention relates to improved means for hermetically closing the tops of tumblers, mugs, and similar plain-rimmed receptacles, and is especially adapted for the sealing of such receptacles by well-known vacuum processes.

Figure 1 of the drawings is a sectional view, in enlarged scale, of the upper left-hand portion of a tumbler, showing my improved closure in its uncomressed or unsealed condition. Fig. 2 is a view similar to that of Fig. 1, but showing the closure in its sealed condition. The section shown in Figs. 1 and 2 is taken on the line 2 2 of Fig. 3. Fig. 3 is a side view, in approximately full-size scale, showing the sealed tumbler, the left-hand upper portion being broken away to show the closure-joint in section. Fig. 4 is a fragmentary side view in section similar to that of Fig. 1, but showing a modified form of cap. Fig. 5 is a fragmentary side view in section, taken on the line 5 5 of Fig. 3, showing, in enlarged scale, the form of the cap-flange. Fig. 5^a is an underneath view of the fluted rim of the caps shown in Figs. 1, 2, 3, and 5. Fig. 5^b is a similar underneath view in section, taken on the line 5^b 5^b of Fig. 5. Figs. 6, 7, 8, and 9 are fragmentary side views, in enlarged scale, showing in section a modified form of my improved closure. Fig. 6 represents the closure as it is initially placed in position prior to the sealing operation. Fig. 7 shows the closure of Fig. 6 in its sealed condition. Figs. 8 and 9 represent these closures as applied to a tumbler having an irregular rim, Fig. 9 being shown in section taken on the line 9 9 of Fig. 8, the latter showing the closure in its unsealed condition, while Fig. 9 shows the closure in its sealed condition. Figs. 10 and 11 are fragmentary sectional views, in enlarged scale, of tumblers, showing some of the different irregularities of contour to which they are liable in commercial manufacture.

The commercial sealing of tumblers and similar round-rimmed receptacles presents difficulties beyond those encountered in the sealing of ordinary jars, which are provided

with an annular shoulder for supporting, leveling, and otherwise positioning the gasket in proper relation to the sealing-joint. The principal of these difficulties in connection with the sealing of tumblers has been to properly seat, centralize, and distribute the gasket upon the tumbler-rim so as to make a commercially-reliable seal. The difficulty is increased by the fact that in the commercial manufacture of tumblers their rims are liable to be more or less uneven both in the contour of the round at different portions of the rim and also in the distortion of the tumbler-rim from a true circle.

The object of the present invention is to provide a closure that will adapt itself to these various inequalities and make an effective seal upon commercially-manufactured tumblers. This is accomplished in the present invention by means of a closure which provides for and directs the distribution of the gasket material upon the tumbler-rim, insuring a suitable thickness or cushion of the gasket material at places where it will fill or compensate for the inequalities referred to, while also providing two or more circles or zones of sealing contact between the tumbler-rim and the cap. The contour of the cap is so related to the contour of the rim that when the cap is pressed down in the sealing operation an annular space of appreciable width is opened between the inside of the cap-flange and the outer side of the tumbler-rim, into which annular space the gasket is compressed by the sealing operation. This annular space allows for considerable variation of the rim from a true circle, since it enables the flexible gasket to flow more or less from one point to the other around the circumference of the rim and also furnishes a sufficient thickness of cushion to permit of considerable variation in the amount of compression while still making a tight joint. This larger portion of the cap-flange extends a substantial distance above the level of the tumbler-rim, so that when the closure is in its compressed or sealed condition there is still a considerable space above as well as on the outer side of the tumbler-rim, this space above the rim allowing the presence of a considerable thickness of the gasket, and thus permitting considerable variation due to the aforesaid depressions or irregularities in the tumbler-rim. In connection with this cap I employ a gasket having a downwardly and outwardly inclined lower edge which rests upon the receptacle-

rim with its acute-angled lower corner projecting in the aforesaid annular space. I prefer to use a gasket or rhomboidal cross-section having cylindrical inner and outer faces and having the top and bottom edges inclined at an acute angle with the said faces. This form of gasket is preferred because in its undistorted or uncompressed form it takes an initial position in the closure-joint most favorable to the perfect and certain sealing of the joint and because it may be cut practically without waste from a long tube of rubber.

The important advantage of compressing the gasket at two or more different circular zones of the tumbler-rim is that if the sealing contact should be imperfect or non-continuous along one of those zones, the chances are good of having at least another line of seal perfect and continuous. This result is due to the fact that the top surface of the cap is depressed to form an annular shoulder and corner over the tumbler-rim, the shoulder serving to resist the tendency of the main body of the gasket when under pressure to escape in an inward direction over the receptacle-rim, while the annular corner catches and pinches a comparatively thin inner portion of the gasket, which as a result of the pressure protrudes inwardly between that corner and the tumbler-rim. This annular corner of the cap thus coöperates with the tumbler-rim to confine the gasket, and thereby insure a greater general compression of the gasket upon the outer zones of the tumbler-rim, and also serves to seal its own special zone of the tumbler-rim.

The tumbler 10 is or may be of the ordinary well-known form having a rounded rim 11, the rims of such receptacles being generally rounded both for appearance and to avoid sharp cutting corners. These rounded rims are liable to imperfections due to their methods of manufacture from wear or mismatching of the mold and mold-rings by which these tumblers are formed, which imperfections are often not removed by the subsequent fire-finishing operation. Moreover, the fire-finishing operation sometimes adds further inequalities due to the unequal application of the heat to different portions of the rim, thereby melting down some portions more than others, as illustrated at 12 in Figs. 8 and 9, and also making the rounded contour of the same portion of the rim unsymmetrical, as shown in Figs. 10 and 11.

The cap 15 is provided with a gasket-receiving portion 16, which is of a diameter substantially larger than the outside of the tumbler-rim 11, this larger portion extending a substantial distance above the level of that rim, even when the closure is in its sealed condition, as shown in Figs. 2 and 4. Portions of the cap-flange are turned inwardly beneath the gasket-seat, so as to engage with the tum-

bler below the rim and centralize the closure therewith. These turned-in portions may be at intervals in the form of the flutes 17, as shown in Figs. 1, 2, and 3, or this turned-in portion may be circular and continuous, as illustrated at 18 in Fig. 4. The enlarged portion 16 provides the annular space 20 outside of the circle of the tumbler rim. The cap-flange being flexible will conform to a considerable degree to the oval or other shape to which the tumbler-rims may be distorted from a true circle. Therefore the annular space 20 will remain substantially uniform in width around the circumference of the rim, so that the gasket, if properly and evenly entered in the space prior to the sealing operation, will be compressed therein with a fair degree of uniformity all around the circle of its portion of the joint.

The gasket 22 is of rhombic form in cross-section, this form being considered by me most advantageous for the present purpose. This gasket is shown in its initial or uncompressed condition in Fig. 1. The cylindrical inner and outer sides 23 and 24 are substantially vertical, the outer side being larger in diameter than the tumbler-rim and approximately fitting the gasket-seat 16, preferably with sufficient tightness to enable it to keep its place in the cap during the handling of the closure prior to and while placing it upon the tumbler. The downwardly and outwardly inclined lower surface 25 of the gasket rests upon the tumbler-rim 11 with the acute-angled lower outer corner 26 projecting into the annular space 20 on the outside of the tumbler-rim, thus insuring the certain and substantially uniform entry of the gasket between the coacting sealing-surfaces on the outer side of the tumbler-rim and on the inner side of the cap-flange.

In the employment of the commoner forms of gasket having circular or other compact cross-sections in connection with a wedging type of closure it is necessary to deform the gasket to a considerable extent from its original form in order to project a sufficient amount of it across the sealing-seat, this deforming operation taking place in connection with the sealing operation itself and being therefore beyond the control and observation of the operator; but in employing the closure herein shown the angular corner 26 projects into the space 20 when the closure is initially placed upon the tumbler prior to the sealing operation, thus permitting the proper initial placing and disposition of the gasket relative to the sealing-surfaces, which is a most important consideration in all hermetic sealing. In the preferred form of this closure (shown in Figs. 1 to 4, inclusive) the complete rhombic form of gasket is employed, having the inclined upper edge 27, the cap being made with a corresponding inclined or conical portion 28, which when the closure is

in its sealed position (shown in Figs. 2 and 4) compresses the gasket at an angle at substantially the line 31. The cap is also provided with an annular corner 35, which in the case of a sheet-metal cap is preferably rounded. That corner is formed by depressing the central portion 36 of the top wall. The corner 35 and the adjacent annular shoulder 37 are disposed on the inner side of the gasket 22, as shown in Figs. 1 and 6, assisting to hold the gasket in the cap while it is being handled and also serving during the sealing operation to prevent the main body of the gasket from being pushed inwardly over the tumbler-rim, thereby tending during the sealing operation to confine the main portion of the gasket to the upper and outer sides of the tumbler-rim. The corner 35 is located over the tumbler-rim, preferably on the inner side thereof, and coöperates with the tumbler-rim to establish an additional or supplemental zone of sealing contact at approximately the line 32 whenever the closure sinks down far enough either from variations in the gasket-space or in the pressure. Thus in the closures shown in Figs. 1 to 4, inclusive, three zones of sealing contact are provided for, (indicated, respectively, by the lines 30, 31, and 32,) the gasket material being so directed and confined as to be compressed at these three zones much more than elsewhere.

When the lower portion of the cap-flange is turned inwardly at intervals in the form of vertical flutes, as shown in Figs. 1, 2, 3, and 5, the lower portions 39 of the space between the inwardly-turned flutes are preferably rounded inwardly at the bottom, as shown in section in Fig. 5, in order to have this portion of the cap smooth, both for appearances and to avoid injury to the persons handling the package. This feature of the cap is more fully illustrated in Figs. 5^a and 5^b. The upper portions 21 of the flute 17 serve as shoulders for supporting the gasket to prevent it from falling out of the cap while being handled prior to placing the closures upon the other receptacles. Thus this portion of the rim of the cap is of a serrated contour, and in order to avoid extending these serrations to the lower edge of the cap-rim I preferably merge the surfaces again into a circular contour at or toward the lower edge 13 of the cap, that edge being therefore circular in form, as best shown in Fig. 5^a. These caps are commonly made from sheet metal by means of drawing dies, which sometimes leave sharp edges or burs or teeth upon the lower edges of the cap-rims, especially where the fluted serrations are extended to the lower edges. Where this cap is to be used upon a tumbler or similar receptacle which has no shoulder in its side wall to underlie the cap-rim, and thus protect the fingers of the user against any injury from its possible sharp or jagged edge, I prefer to make the circular edge 13 of

the cap-rim fit quite closely against the wall of the receptacle, as is shown in Figs. 1 and 2, thus making it of a diameter smaller than the diameter of the gasket-seat. In that case the portions 39 of the turned-in intervals between the flutes serve to guard the user's fingers from any injury from sharp edges; but the position and diameter of the circular edge 13 of the cap relative to the gasket-seat 16 are matters which should be determined by circumstances, including the characteristics of the receptacle itself, it being obvious that the serrated portions may be merged at or toward the edge of the cap into a circle of any desired size relative to the diameter of the gasket-seat.

In the closure shown in Fig. 4 the annular corner 40 is more acute, due to the fact that the middle portion 41 of the cap 42 is turned upwardly inside of the corner 40, that corner being, in effect, an annular bead projecting downwardly from the upper wall of the cap. This form of corner narrows the line of pinch, and hence with the same amount of pressure makes a more sharply-defined circle of contact.

In the form of closure shown in Figs. 6 to 9, inclusive, the gasket 43 differs from that of the preceding figures in the respect that the upper surface 44 is approximately flat instead of being inclined and the corresponding portion 49 of the cap 48 is rounded above the gasket; but aside from this difference in detail the construction and mode of operation are substantially the same as that of the closure of the preceding figures, excepting that this form of closure establishes two zones of contact 45 and 46, as shown in Fig. 7, instead of three zones, as shown in Fig. 2.

Figs. 8 and 9 represent the action of the closure when employed upon tumblers having irregular rims. As shown in Fig. 9, the gasket 43 when compressed sinks into the depression 12 on account of the cushion of the gasket material which lies above and around it. Moreover, the annular space at the point 47 is not appreciably affected by the depressions in the top of the rim. Therefore the joint at 47, corresponding with the zones 30 and 45 of Figs. 2 and 7, respectively, will be practically as good as though the adjacent top portion of the rim were of full height.

In the case of irregularities in the rounded contour of the rim like those shown in Figs. 10 and 11 the depressions at one side do not ordinarily affect the adjacent portions of the rim, so that an effective seal is made at one or the other of the sealing-zones 45 and 46. In the case of the closure shown in Figs. 1 and 2 the additional zone 31 still further lessens the chances of leakage or failure due to the imperfections referred to. The increased cushioning effect obtained by this closure does not necessarily involve the use of an in-

creased amount of gasket material, but is mainly effected by the proper initial disposition and distribution of the gasket material, in connection with the use of a flexible cap 5 having a suitable contour for confining and directing the flow of the gasket material during compression, all of which results in distributing the gasket material between two or more narrow sealing-zones, utilizing the 10 space or spaces between those zones as reservoir-space from which the gasket material flows to the respective sealing-zones as the need therefor is developed during the sealing operation and in accordance with the requirement of each individual tumbler, instead of wasting the material by allowing a 15 considerable volume of it to protrude uselessly at one or both sides of the closure-joint.

These improved closures may be manufactured and used and sold quite independently of the tumblers which they are intended to seal, the gasket being seated within the cap securely enough to prevent displacement during any handling to which it may be subjected. 20 These closures may be sealed in any of several well-known ways. I prefer, however, to seal them by the process described and claimed in United States Patent No. 711,431, of October 14, 1902. It is obvious, 25 however, that the closures may be sealed in many ways, either by hot or cold processing.

During the sealing operation the closure is moved downwardly from its initial position (shown in Fig. 1) toward its sealed position, 30 (shown in Fig. 2,) the annular space 20 beneath the gasket and on the outer side of the tumbler-rim being extended downwardly. The pressure of the cap upon the top portion of the gasket being downward and the lower 35 side of the outer edge of the gasket being left without support over the annular space 20, the lower edge of the gasket is naturally and inevitably forced into that space, the downward and outward inclination of the lower side 40 of the gasket and of its coacting rounded edge of the tumbler-rim tending also to favor this direction of flow of the gasket. The contraction of the annular gasket-space above the rim being much greater than the extension of the space 20 below the rim, the result 45 is a sort of differential action by which the lower edge of the gasket is compressed into the mouth of the annular space 20; thereby first establishing a definite zone of pressure 50 approximately at the line 30. Unless and until the compression of the zone 30 becomes sufficient in itself to sustain the pressure upon the cap the continued downward movement of the cap still further compresses the gasket-space, so that a fin of the gasket is protruded 55 inwardly over the tumbler-rim, beneath the rounded corner 35, which if the downward movement continues far enough coacts with the inner rounded portion of the rim to establish a sealing-zone approximately at the 60

line 32, while the conical portion 28 of the cap establishes another zone of seal approximately at the line 31. In this way precedence is given to the zone 30, the balance of the gasket material after attending to that zone being distributed to and compressed upon the other zones 31 and 32.

I claim as my invention—

1. The combination with a tumbler or similar receptacle having a rounded rim, of a hermetic closure therefor, consisting of a cap, provided with a flexible flange having an annular portion substantially larger in diameter than the receptacle-rim, and extending a substantial distance above the level of the rim, an annular gasket seated in said larger portion and having its lower edge disposed at an acute angle extending downwardly into the annular space between the receptacle-rim and the cap-flange, the cap being provided with an annular shoulder projecting downwardly on the inner side of the top of the gasket to support the top of the gasket against inward movement during the sealing operation, terminating in a corner which overlies and coacts with the rounded rim to engage the portion of the gasket which protrudes inwardly between them.

2. The combination with a tumbler or similar receptacle having a rounded rim, of a hermetic closure therefor, consisting of a cap provided with a flexible flange having an annular portion substantially larger in diameter than the receptacle-rim and extending a substantial distance above the level of that rim, an annular gasket seated in said larger portion with the greater portion of its bulk disposed outside of the circle formed by the crown of the tumbler-rim, a portion of the top wall of the cap being depressed within the circle of the gasket, to form an annular shoulder, the lower corner of which overlies the inner rounded portion of the receptacle-rim, whereby that portion of the gasket which protrudes inwardly over the tumbler-rim is held between said shoulder and the said rounded portion of the receptacle-rim.

3. The combination with a tumbler or similar receptacle having a rounded rim, of a hermetic closure therefor, consisting of a cap provided with a flexible flange having an annular portion substantially larger than the receptacle-rim, and extending from below the level of the rim a substantial distance above that level, and an annular gasket seated in said larger portion and having its outer and lower edge disposed at an acute angle extending downwardly into the annular space between the receptacle-rim and cap-flange, whereby said gasket is forced downwardly during the sealing operation into the said annular space, the cap being also provided with a downwardly-projecting annular corner overlying the inner rounded portion of the receptacle-rim, whereby the portion of the

gasket which protrudes inwardly over the receptacle-rim is compressed between the said rim and the said corner.

4. The combination with a tumbler or similar receptacle having a rounded rim, of a hermetic closure therefor, consisting of a cap provided with a flexible flange having an annular portion larger in diameter than the receptacle-rim, and extending a substantial distance above the level of the rim, and an annular gasket seated in said enlarged portion with its lower and outer edge disposed at an acute angle extending into the annular space between the receptacle-rim and the cap-flange, whereby it is forced downwardly and pinched between the rim and the flange by the sealing operation, the cap being provided with a contracted portion extending inwardly beneath the edge of the gasket into substantial contact with the receptacle, to center the closure thereon, and the cap being also provided with an annular shoulder projecting downwardly within the top of the gasket and forming an annular corner coacting with the rounded edge of the receptacle to engage an inner zone of the gasket between them.

5. The combination with a tumbler or similar receptacle having a rounded rim, of a hermetic closure therefor, consisting of a cap provided with a flexible flange having an enlarged portion substantially larger in diameter than the receptacle-rim, and extending a substantial distance above the level of the rim at all positions of the closure, an annular gasket seated in said enlarged portion, with its lower edge inclined downwardly and outwardly across the outer rounded portion of the receptacle-rim, and with its upper edge inclined upwardly and inwardly, the cap being provided with an annular beveled portion substantially conforming with the inclined upper edge of the gasket for wedging the said inclined portion downwardly upon the receptacle-rim.

6. The combination with a tumbler or similar receptacle having a rounded rim, of a hermetic closure therefor consisting of a cap provided with a flexible flange having an enlarged portion substantially larger in diameter than the receptacle-rim, and extending a substantial distance above the level of the rim in all positions of the closure, an annular gasket seated in said enlarged portion, with its lower edge inclined downwardly and outwardly across the outer rounded portion of the receptacle-rim, and with its upper edge inclined upwardly and inwardly, the cap being provided with an annular beveled portion substantially conforming with the inclined upper edge of the gasket for wedging the said inclined portion downwardly upon the receptacle-rim, and having also an annular shoulder projecting downwardly within the circle of the gasket and forming an annular corner

coacting with the inner portion of the rounded rim to pinch an inner zone of the gasket between them.

7. The combination with a tumbler or similar receptacle having a rounded rim, of a hermetic closure therefor consisting of a gasket having approximately cylindrical inner and outer faces and having inclined upper and lower edges forming acute angles with the said inner and outer faces respectively, a cap provided with a flexible flange forming a seat approximately conforming to the outer face and upper inclined edge of said gasket, the cylindrical portion being substantially larger in diameter than the receptacle-rim, and extending a substantial distance above the level of that rim in all positions of the closure.

8. The combination with a tumbler or similar receptacle having a rounded rim, of a hermetic closure therefor consisting of a gasket having approximately cylindrical inner and outer faces, and having inclined upper and lower edges forming acute angles with the respective faces, a cap provided with a flexible flange forming a seat approximately conforming to the outer face and upper inclined edge of said gasket, the cylindrical portion of the seat being substantially larger in diameter than the receptacle-rim, and extending a substantial distance above the level of that rim in all positions of the closure, portions of the flange being turned inwardly beneath the gasket to center the closure with the receptacle.

9. The combination with a tumbler or similar receptacle having a rounded rim, of a hermetic closure therefor consisting of a gasket having approximately cylindrical inner and outer faces and having upper and lower edges forming acute angles with the respective faces, a cap provided with a flexible flange forming a seat approximately conforming to the outer face and upper inclined edge of said gasket, the cylindrical portion of the flange being substantially larger in diameter than the receptacle-rim, and extending a substantial distance above the level of that rim in all positions of the closure, portions of the flange being turned inwardly beneath the gasket to center the receptacle with the closure, and a portion of the top of the cap being depressed to form an annular shoulder coacting with the interior portion of the rounded rim of the receptacle to engage an inner zone of the gasket between them.

10. The combination with a tumbler or similar receptacle, of a hermetic closure therefor, consisting of a gasket having an outer diameter substantially greater than that of the tumbler-rim, and a cap having a flexible flange provided with a portion engaging the receptacle below the rim to centralize the closure therewith, and having a larger cylindrical portion extending above the level of

said rim merging into an inwardly-inclined conical portion and thence merging into a downwardly-projecting portion providing a corner located above and coacting with the 5 rounded rim to engage an inner zone of the gasket between them.

11. The combination with a tumbler or similar receptacle having a rounded rim, of a hermetic closure therefor, comprising a cap 10 having a flexible flange forming a cylindrical gasket-seat of a diameter substantially larger than that of the receptacle-rim, merging into a conical portion, inclined inwardly over the receptacle-rim and thence downwardly to 15 form an annular shoulder situated above the said rim, and a gasket substantially fitting the cylindrical gasket-seat, the thickness of the gasket being substantially greater than the width of the annular space between the 20 rim and the cap-flange, whereby the gasket is compressed against different zones of the tumbler-rim by the cylindrical portion, the conical portion and the corner portion of the cap.

25. 12. A hermetic closure for receptacles, comprising a cap having an annular gasket-seat, and having portions of its rim turned inwardly at intervals to form a supporting-shoulder beneath the gasket, merging again 30 into circular contour below the shoulder.

35. 13. A hermetic closure for receptacles, comprising a cap provided with an annular seat, and having portions of its rim turned inwardly at intervals below the gasket-seat 35 to support the gasket, the turned-in portions merging again into coincidence with the other portions of the rim to form a circular-edged rim.

40. 14. A hermetic closure for receptacles, comprising a cap having an annular gasket-seat, and having portions of its rim turned

inwardly at intervals below the gasket-seat to form supporting-shoulders for the gasket, the portions of the rim below the said shoulders merging into a circular contour of a 45 diameter smaller than that of the annular gasket-seat.

15. A hermetic closure for receptacles, comprising a cap having an annular gasket-seat, and having portions of its rim turned 50 inwardly at intervals beneath the gasket to form vertical flutes for supporting the gasket, the said fluted portions terminating at their lower ends in a circular contour coincident with the intervening portions of the 55 rim.

16. A hermetic closure for receptacles, comprising a cap provided with an annular gasket-seat, and having portions of its rim turned inwardly at intervals beneath the 60 gasket-seat to form vertical flutes for supporting the gasket, the said flutes terminating at their lower portions in a circular contour coincident with the intervening portions of the cap-rim, and of a diameter less 65 than that of the annular gasket-seat.

17. A hermetic closure for receptacles, comprising a cap provided with an annular gasket-seat, and having portions of its rim turned inwardly below the gasket-seat to 70 form vertical flutes for supporting the gasket, the lower portions of the cap-rim intermediate the flutes being turned inwardly into circular coincidence with the bottom portions of the flutes. 75

In testimony whereof I have signed my name to this specification in the presence of two subscribing witnesses.

WILLIAM A. LORENZ.
